United States Patent Office

Des. 206,177
Patented Nov. 8, 1966

206,177

COMBINED SNOW SHOVEL AND CART

Oliver K. Unruh, 615 Chestnut St., McPherson, Kans.

Filed Sept. 15, 1965, Ser. No. 87,009

Term of patent 14 years

(Cl. D35—2)

FIG. 1

FIG. 2

FIG. 4

FIG. 3

FIG. 1 is a side elevation view of a combined snow shovel and cart showing my new design; and

FIG. 2 is a top plan view of same; and

FIG. 3 is a rear elevation view of same; and

The other side is substantially the same in appearance as that of FIG. 1.

I claim:

The ornamental design for a combined snow shovel and cart, substantially as shown and described.
